UNITED STATES PATENT OFFICE

LEWIS C. MARSHALL, OF WALPOLE, MASSACHUSETTS, ASSIGNOR, BY MESNE ASSIGNMENTS, TO THE SIMPLEX PISTON RING COMPANY OF AMERICA, INC., OF CLEVELAND, OHIO, A CORPORATION OF OHIO

PISTON PACKING

Application filed February 13, 1925, Serial No. 8,933. Renewed January 12, 1932.

This invention pertains to metallic piston packings and more particularly to split ring packings of the type employed in internal combustion engines.

5 Principal objects of the invention are to provide a packing ring furnished with oil scraping and receiving means; to provide an improved packing of simple and sturdy construction applicable to one piece pistons having 10 circumferential packing grooves of fixed width and inherently capable of close contact with the opposite side walls of the piston groove; to provide a unitary split ring slotted to make it axially resilient, or compressible 15 and which can be manufactured rapidly and without excessive labor; to provide a one piece axially resilient split ring free from thin and fragile tongues or projections at its ends; and to provide a split ring which is 20 axially resilient at substantially all points of its circumference including the regions of the split or gap.

In the accompanying drawing one preferred embodiment of the invention is disclosed by way of example together with certain modified features of construction which may or may not be combined with one another as experience or circumstances may warrant.

25 Fig. 1 is a perspective view of a split ring packing embodying the present invention, showing such packing as comprising a main outer ring having series of inclined slits therethrough, and an inner follower or expander ring, the forward portion of the latter being broken away,—

Fig. 2 is a fragmentary radial section through a piston showing the ring of Fig. 1 seated in the piston groove;

30 Figs. 3, 4 and 5 are views similar to Fig. 2 but illustrating modified forms of main and expander rings;

Fig. 6 is a fragmentary developed view of the ring of Fig. 1 showing one arrangement of the split or gap designed to make the ring resilient at opposite sides of the gap;

Fig. 7 is a view similar to Fig. 6 showing a modified arrangement providing greater 35 axial resiliency;

Figs. 8, 9, 10 and 11 are fragmentary developed views also showing rings rendered resilient by the provision of inclined slits and illustrating various modifications of the split or gap and of the end portions of the ring; 55

Figs. 12, 13, and 14 are fragmentary developed views showing axially resilient rings having slits in planes perpendicular to the axis of the ring, illustrating various modes 60 of making the rings resilient in the neighborhood of the gap.

Referring to the drawing the numeral 1 designates a packing ring which may be used alone in the piston groove, or, as here illustrated, be associated with an internal expander ring 2 of any usual construction.

The ring 1 is provided at one point with the usual transverse gap, indicated at 3, which permits the ring to expand radially. 70 In the preferred form of packing herein illustrated the main ring 1 is rendered axially compressible or resilient by providing it with a plurality of over-lapping slits 4 which extend through the entire radial thickness of the ring and which are disposed in planes inclined to the plane of the ring. Preferably, the angle between the plane of a slit and the plane of the ring is not over 45°, although a greater angle may sometimes prove desirable, 75 but whatever the angle of the slits, the latter are closed at both ends, leaving the upper and lower edges of the ring smooth and continuous except at the gap 3.

Referring to Fig. 2 a portion of the side wall of an engine piston is indicated in section at 5, such wall being provided with the usual circumferential groove 8 in its outer surface for the reception of the packing ring. This groove is formed with spaced side walls 6 and 7 respectively which are perpendicular to the axis of the ring. The ring 1 is normally somewhat wider in an axial direction than the groove in the piston and in order to seat the ring in the groove it is necessary to compress the ring axially. When compressed the ring may be slipped into the groove and then by its inherent resiliency it presses in opposite directions against the walls 6 and 7 of the groove so that reciproca- 85 90 95 100

tion of the ring in the groove is entirely prevented. The ring thus devised, effectually prevents oil pumping, with its attendant harmful effects, and as the ring cannot tip or rock, due to its snug engagement with the parallel walls 6 and 7 of the groove, it maintains a more perfect contact with the cylinder wall and for a greater length of time, than does the ordinary ring.

- 10 As shown in Fig. 2 the main ring 1 is furnished with a groove upon its inner peripheral surface, such groove having bevelled upper and lower faces, and the expander ring 2, arranged behind the main ring, has a curved outer surface which bears against the inclined faces of the groove of the main ring 1.

In Fig. 3 I have illustrated a main ring 1^c which may be of the type illustrated in Fig. 1 or of any of the other types hereafter described. In this arrangement no expander ring is employed and the inherent tendency of the split ring 1 to expand radially is depended upon to hold it in contact with the cylinder walls.

In Fig. 4 I have illustrated a further modified form of main ring designated 1^e. This ring is provided at its inner face with a groove similar to that of the ring 1 shown in Fig. 2 but the expander ring 2^a is furnished with bevelled faces engageable respectively with the bevelled surfaces of the groove.

In Fig. 5 the main ring 1^b is of further modified construction having a groove of arcuate contour at its inner face, and the expander ring 2^b is formed of round or other suitably shaped wire in the usual manner, such ring engaging the concave surface of the groove of the main ring.

40 Referring to Fig. 6 which shows a fragmentary developed portion of the main ring of Fig. 1 the end most slits of the series of slits 4 are indicated by the numerals 4^a and 4^b respectively.

45 The gap in the ring which permits it to expand radially comprises two circumferentially offset axially extending slots 3^a and 3^b respectively united at their inner ends by a circumferential slot 3^c. This arrangement provides over-lapping tongues 9 and 10 at the ends of the ring, and in the arrangement here illustrated the endmost slits 4^a and 4^b extend into these tongues and almost to the extremities of the latter. However, the slits 50 do not extend entirely to the ends of the tongues so that the ends of the slits are closed by solid metal. This arrangement provides for over-lap of the slits 4^a and 4^b when the ring is closed so that the axial resiliency or 55 compressibility of the ring is maintained even at the region of the gap but without leaving the ends of any of the slits open.

If the ends of the slits were left open at opposite sides of the gap the resulting long 60 thin tongues of metal supported only at one

end would be so fragile and easily broken as to make the ring troublesome to handle, but by the present arrangement this difficulty is avoided and the meeting faces of the ring are imperforate and strong while at the same time the ring is axially compressible at the region of the gap.

70 In the arrangement shown in Figs. 1 and 6 the slits 4 over-lap somewhat less than one half of their respective lengths but in the ring 20 shown in Fig. 7 the slits 24 overlap a distance greater than one-half their respective lengths so that at any section, for example that indicated by the line a—b, at least three slits will be found in over-lapping relation. A ring thus formed is even more compressible and resilient in an axial direction than the ring of Fig. 1, and it is clear, that if the ring be of sufficient width to permit it, an even greater overlap of the slits, with corresponding increase in axial resiliency may be obtained.

75 In the arrangement shown in Fig. 7 the ring 20 is provided with a gap conveniently formed by extending slots 23^a and 23^b inward from opposite edges of the ring to merge into one of the inclined slits of the ring. This particular slit, designated 23, may if desired, be somewhat widened in order 80 to provide the proper space between the meeting ends of the ring.

85 In this arrangement as well as in that shown in Fig. 6 the endmost slits of the series extend well down into the overlapping end 90 portions of the ring so as to maintain the resiliency of the ring throughout.

95 In the arrangement shown in Fig. 8 the ring 30 is provided with inclined slits 34 to make it axially resilient and at offset points slots 33^a and 33^b are extended inwardly from opposite edges of the ring to intersect one of the slits, for example the slit 33, of the series of inclined slits. In this case the slots 33^a and 33^b intersect the slit 33 at points intermediate the ends of the latter. This arrangement may be found desirable under certain circumstances although that shown in Figs. 6 and 7 is regarded as preferable.

105 Referring to Fig. 9 the ring 40 is shown as provided with inclined slits 44 and the gap in this ring is formed by a single inclined slot 43 which intersects one of the slits 44, for example the slit 44^a, substantially at its central portion. In this arrangement the meeting ends of the ring are not solid, but nevertheless the formation of thin and narrow tongues of metal is substantially avoided.

115 In Fig. 10 the ring 50 is shown as provided with inclined slits 54 to make it axially resilient and is furnished with a slot 53 providing a gap in the ring. This slot 53 extends diagonally through the ring and is inclined oppositely to the slits 54. The slot 120

53 forms overlapping end portions 59 and these end portions are made axially resilient by the provision of slits 55 and 56 which in this case are parallel to the plane of the ring and which overlap each other and also the ends of the adjacent slits 54.

The arrangement shown in Fig. 11 resembles that shown in Fig. 1 in many respects as the ring 60 is provided with a series of inclined slits 64 and with a gap 3 to make the ring radially resilient, but in this case the slits 64 do not overlap to any substantial extent so that the ring is not compressible in an axial direction to any appreciable degree. While the ring thus devised is not as desirable from many standpoints as the other forms of ring illustrated it may be used in the manner of an ordinary packing ring but with the advantage of having oil scraping means extending throughout its entire circumference. While no continuous groove of the type commonly employed for oil scraping is provided, the ultimate effect of the series of slits 64, so far as oil scraping is concerned is substantially the same as that of a single continuous groove.

In Fig. 12 the ring 70 is shown as provided with overlapping slits 74 arranged in planes parallel to that of the ring. The ring is furnished with a diagonal gap 73 which defines overlapping end portions 79 of the ring and these end portions are rendered axially resilient by means of inclined slits 75 which overlap each other and the adjacent slits 74.

In Fig. 13 the ring 80 is made axially resilient by overlapping slits 84 and the gap in the ring comprises inwardly directed slots 83 intersecting the inclined slot 83^a. The overlapping portions 89 of the ring are made axially resilient by extending the endmost slits 84 into these overlapping portions so that the endmost slits overlap each other. If desired, these endmost slits may be special slits, shorter than the slits of the series proper, although ordinarily this is not necessary.

In Fig. 14 the ring 90 is shown as provided with overlapping slits 94 arranged in planes parallel to the plane of the ring and the gap in the ring comprises inwardly directed offset slots 93^a intersecting a slot 93^b which is parallel to the plane of the ring. In this case also the overlapping end portions of the ring are axially resilient.

While I have endeavored to show various desirable embodiments of the invention it is to be understood that the invention is not necessarily limited in its application to the arrangements herein specifically shown and described but that it is undoubtedly capable of embodiment in other specific arrangements which will occur to those skilled in the art. It is also to be understood that the invention is not limited to the particular proportions of parts herein illustrated or to any specific combination of main and expander rings or to

any particular material, and that while the packing is particularly designed and intended for use in the pistons of internal combustion engines it is not necessarily limited to such use.

I claim:

1. A piston packing comprising a main split ring provided with a plurality of slits extending through its entire radial thickness, said slits being so disposed in planes inclined to the plane of the ring as to make the ring axially elastic, and a follower ring engaging the inner surface of the main ring and arranged to exert force on the main ring tending to expand it axially and radially.

2. A piston packing comprising a main split ring provided with a circumferential groove in its inner peripheral surface, and having narrow slits extending through its entire radial thickness, said slits being inclined to the plane of the ring and overlapping at their ends the angle of inclination of the slits to the plane of the ring being less than 45°, whereby to render the ring axially resilient, and a follower ring engaging the groove in the inner surface of the main ring.

3. A split packing ring provided with a plurality of narrow overlapping slits passing through its entire thickness, said slits being closed at both ends, the slits being disposed in planes inclined to the plane of the ring at such angles as to render the ring axially elastic.

4. A piston packing comprising a split main ring provided with a plurality of narrow slits closed at both ends extending through its entire radial thickness, said slits being disposed in planes inclined to the plane of the ring, and a radially expansible follower ring engaging the inner surface of the main ring.

5. A packing ring provided with a gap at one point, said gap being so arranged that the end portions of the ring overlap to break the joint, said ring having a plurality of narrow slits extending through its entire radial thickness and so disposed as to make the ring axially elastic, and other slits, similar to but lying in planes intersecting the planes of the first slits disposed respectively in the overlapping end portions of the ring.

6. A packing ring provided with a gap at one point, the ends of the ring overlapping at the gap to break the joint, said ring being provided with a plurality of slits extending through its entire radial thickness, some at least of said slits being inclined to the plane of the ring and certain slits extending into the overlapping end portions of the ring.

7. A packing ring provided with a gap at one point, the ends of the ring overlapping at the gap to break the joint, said ring being provided with a series of overlapping slits passing through its entire radial thickness, said slits being inclined to the plane of the

130

ring, and other slits lying in planes substantially perpendicular to the axis of the ring extending into said overlapping end portions.

5 8. A split packing ring provided with slits extending through its entire thickness in a radial direction, said slits being closed at both ends and inclined to the plane of the ring, the end of one slit being disposed closely adjacent to one edge of the ring and the end of the next slit being disposed closely adjacent to the opposite edge of the ring.

15 9. A split packing ring provided with a series of slits each extending through its entire thickness in a radial direction and each closed at both ends, the slits of said series being staggered and the end of one slit being disposed adjacent to one edge of the ring and the end of the next slit being disposed adjacent to the opposite edge of the ring, each slit of the series being inclined to the plane of the ring at an angle not greater than 45°, the aggregate effect of the series of slits being similar to that of a single continuous 20 circumferential oil scraping groove opening from the exterior to the interior of the ring.

30 10. In a piston ring having parallel axial faces, a series of inclined overlapping slots extending through the ring, the axial faces of the ring being split at points on both sides of the middle of one of said inclined slots by parallel cuts which extend from said slots to the respective axial faces, thus forming a 35 step junction.

40 11. In a piston ring having parallel axial faces, a series of inclined overlapping slots extending through the ring, the axial faces of the ring being split at points on both sides of the middle of one of said inclined slots by parallel cuts which extend from said slot to the respective axial faces, thus forming a 45 step junction, both ends of said junction being symmetrical.

45 12. In a piston ring having parallel axial faces, a series of inclined overlapping slots extending through the ring, the axial faces of the ring being split at points on both sides of the middle of one of said inclined slots by parallel cuts which extend from said slot to the respective axial faces, the portion of inclined slot between the cuts being the overlap, and the respective overlapping faces being 50 spaced apart from each other.

55 Signed by me at Boston, Massachusetts,
this 12th day of February, 1925.

LEWIS C. MARSHALL.
